HOLDING FIXTURE FOR ENGINE HEADS

Gordon Louis Greene, 818 Bald Eagle Ave.,
White Bear Lake, Minn. 55110

Filed Apr. 4, 1968, Ser. No. 11,306

Term of patent 14 years

Int. Cl. D15—05

U.S. Cl. D54—13

FIG. 1 is a perspective view of the holding fixture for engine heads showing the embodiment of my new design;

FIG. 2 is a top plan view of the holding fixture; and

FIG. 3 is a section view as observed along viewing line 3—3 of FIG. 2.

I claim:

The ornamental design for a holding fixture for engine heads, as shown.
